[57] CLAIM

The ornamental design for a refrigerator grill, as shown and described.

DESCRIPTION

FIG. 1 is a perspective view taken from the top, front and right side of a refrigerator grill showing my new design;

FIG. 2 is a right side elevational view thereof, the left side being the mirror image of the right side shown;

FIG. 3 is a top plan view thereof;

FIG. 4 is a front elevational view thereof;

FIG. 5 is a bottom plan view thereof;

FIG. 6 is a perspective view taken from the top, front and right side of a second alternative embodiment thereof;

FIG. 7 is a right side elevational view thereof, the left side being the mirror image of the right side shown;

FIG. 8 is a top plan view thereof;

FIG. 9 is a front elevational view thereof; and,

FIG. 10 is a bottom plan view thereof.

FIG. 1

FIG. 2

FIG. 3

FIG. 4
